UNITED STATES PATENT OFFICE.

THORVALD BRANDT, OF BADEN, GERMANY.

BUCKLE FOR SECURING STRAPS.

SPECIFICATION forming part of Letters Patent No. 448,496, dated March 17, 1891.

Application filed October 28, 1890. Serial No. 369,639. (No model.)

To all whom it may concern:

Be it known that I, THORVALD BRANDT, joiner, of Baden-Baden, in the Grand Duchy of Baden, and German Empire, have invented 5 new and useful Improvements in Buckles for Securing Straps, of which the following is a specification, reference being had therein to the accompanying drawings.

This invention relates to buckles for fastening straps of leather or other material, especially leather harness-straps of large size.

The buckles hitherto used, particularly when employed with heavy leather straps, are difficult to fasten and equally difficult to unfasten.

The object of the present invention is to provide a buckle suitable for use with heavy leather straps and capable of being easily manipulated.

20 In the accompanying drawings, Figure 1 is a longitudinal section showing a buckle constructed according to this invention and serving to connect two straps or the ends of a belt. The position of the parts when the buckle is 25 open is indicated by dotted lines. Fig. 2 is a plan of the buckle when open, the straps being omitted. Fig. 3 is an end elevation of the opened buckle, the straps or the ends of the belt being represented in transverse section.

30 Fig. 4 is a perspective view of the fastening-plate.

To the strap A is secured a plate B, from which project at right angles two side pieces D and D'. The fastening-plate G is pivoted 35 on the pin E and carries a stud H, which passes through any one of the holes i i in the strap K and into the hole C in the plate B.

A locking-plate L, having a projection or toe M and a catch O, is pivoted on the pin F and serves to raise and lower and lock in the lowered position the plate G, which is formed with an upwardly-projecting tongue R.

The action of the parts is as follows: In raising the plate L from the position shown in Fig. 1 to the position indicated by dotted lines 45 in that figure the toe M engages with the tongue R and raises the fastening-plate G, thus withdrawing the stud H, so that the end of the strap K can be readily pulled out of the buckle. In depressing the plate L into its 50 normal position the toe M slides over the surface of the plate G (which may be hollowed, as shown at N) and causes the plate G to return to the position shown in Fig. 1, the stud H passing through one of the holes i and into 55 the hole C. Finally, the catch O snaps over the knuckle P of the plate G, and the parts are securely locked in the closed position.

What I claim, and desire to secure by Letters Patent of the United States, is—

60 The improved buckle for securing straps or belts, constructed substantially as herein described and having a fastening-plate G, provided with a stud H and a tongue R, a pivoted locking-plate L, formed with a toe M, the plate 65 G being raised or depressed by the plate L accordingly as the toe of the latter engages beneath the tongue R or against the back of the plate G.

Mannheim, September 15, 1890.

THORVALD BRANDT.
